REMINDING DEVICE

Harry T. Butler, Garvey, Calif.

Application November 20, 1939, Serial No. 305,234

3 Claims. (Cl. 116—135)

My invention relates to a reminding device and more particularly to a device by which housewives may remind themselves of supplies that are needed for the household.

5 An important object of the invention is to eliminate the use of pegs that have to be withdrawn from a board and inserted into sockets.

It is an object of my invention to provide quicker and simpler means for reminding a housewife, without the use of said pegs and sockets and without the use of a pencil.

The invention also comprises novel details of construction and novel combinations and arrangements of parts, which will more fully appear in the course of the following description. However, the drawings merely show and the following description merely describes an embodiment of the present invention, which is given by way of illustration or example only.

20 In the drawing, like reference characters designate similar parts in the several views.

Figure 1 is a face view of an embodiment of a device carrying out the foregoing objects.

Figure 2 is a broken, transverse section taken 25 on the line 2—2 of Figure 1.

Figure 3 is a broken, vertical section taken on the line 3—3 of Figure 1.

Referring more in detail to the drawing, the reference numeral 4 indicates a back member or board upon the face of which is a series of names 5 of household articles. Suitable spaces 6 may be arranged adjacent the names 5, in which the housewife may write the names of other articles or other household duties, such as "laundry," etc.

40 A space 7 is provided at the top of the back member 4 which may contain a slogan to remind the housewife to use the board or it may contain an advertisement, if the present device is distributed as an advertising novelty. At the bottom of the back member 4 a pad 8 may be provided. The pad 8 may be either a blank memorandum pad or a calendar pad, or instead of the pad 8 an advertisement may be printed 45 in the space covered by the pad 8. An opening having an eyelet 10 is provided at the top of the back member 4, in the center thereof.

It is to be understood that a tack or nail 9 may be used to hang the device on a cupboard 50 door or other appropriate place. The opening is of sufficient size for the back member 4 to freely swing around the tack or nail 9 as an axis. The purpose of this free swinging action will be explained hereinafter.

55 Mounted upon the face of the back member 4

is a channel member 12 provided with flanges 13. The channel member is mounted on the back member 4 by means of three lugs 14, 15 and 16. The lugs 14 and 16 extend from the ends of the channel member 12. Three sides of the lug 15 are stamped out of the floor of the channel 12, as shown at 17, and after insertion through a slit in the back member 4 the lug 15 is bent downward against the back of the member 4 substantially to the broken line position shown at 15 in the drawing. The lug 15 thereby maintains the mid-portion of the channel member 12 against the face of the board 4.

It is to be understood that the lugs 14 and 16 are also inserted through slits in the back member 4 and after such insertion the lugs are bent against the back of the board member 4, the same as the lug 15. The lug 14 is normally bent downward and the lug 16 is normally bent upward, as shown in broken lines in the drawing.

Freely slidable in aligned openings in the flanges 13 is a series of pins 18. The pins 18 may be made of nail stock or other suitable material. One end of each pin 18 is bent substantially at right angles, as shown at 19. The other end of each pin 19 carries a head 20. The bent ends 19 and the heads 20 limit lengthwise movement of the pins 18 in the openings in the flanges 13.

In the use of the present device, the pins 18 are normally to the left, as shown by the top six pins in Figure 1. When the housewife desires to remind herself to purchase further commodities, she pushes the respective pins to the right, as shown in Figure 1. As examples, Figure 1 shows that the housewife wishes to purchase more "flour," "milk" and "tea." Under normal conditions of use in the above described manner, it will be noted that, since the pins 18 are mounted through openings of both flanges 13 of the channel member 12 and are of substantially greater length, along their extended portions in each extended position, than the space between the flanges, the weight of the extended portions acts by leverage to promote frictional engagement between the pins and the flanges at those points where the pins are within the openings of the flanges. Thus the pins act of their own accord to steady the same against accidental displacement. It is also to be observed that, by the use of lengthwise, shiftable pins, all danger of mistake as to the indicated commodity is removed, since when extended to indicating position, each pin will overlie, and partially obscure the name of its re-

spective commodity. There is thus no necessity of sight alinement of indicator and commodity name and danger of error is minimized.

After replenishing her supply of these com-

- 5 modities, the housewife can very quickly return the pins to their original position, in which the heads 20 contact the nearest flange 13. This restoration of the position of the pins is very quickly effected by swinging the entire back mem-
10 ber 4 in the direction of the arrow A, around the tack or nail 9 as an axis. Since the pins 18 are freely slideable in the flanges 13, the pins that have been moved to the right will slide back to their original positions by one simple swinging
15 motion of the board 4 in a counter-clockwise direction. The board is then returned to its normal, vertical position and all of the pins 18 have their heads contacting the adjacent flange 13.
20 While I have illustrated and described what I now regard as the preferred embodiment of my invention, the construction is, of course, subject to modifications without departing from the spirit and scope of my invention. I, therefore,
25 do not wish to restrict myself to the particular form of construction illustrated and described, but desire to avail myself of all modifications which may fall within the scope of the appended claims.
30 Having thus described my invention, what I claim and desire to secure by Letters Patent is:

1. A household reminder comprising a back member mounted to swing about a fixed axis, a channel member on the back member presenting
35 spaced parallel flanges, and a series of pins freely slideable through openings in both flanges of the channel member and arranged to be slid to a desired position on the channel member by swinging motion of the back member about said
40 axis, said pins being manually slideable beyond

opposite sides of the channel member and, when so extended, presenting portions beyond said member of substantially greater length than the space between said flanges.

2. A household reminder comprising a back 5 member having thereon a series of names of commodities, a channel member on the back member at one side of said series of names, hav-
10 ing spaced flanges, a series of pins slideable later-
ally through both flanges of the channel member, in the direction of said names respectively, and abutment means on the pins limiting movement of the pins in the channel member the pins when extended to one side of the channel member over-
lying and partially obscuring respective names of 15 said series of names.

3. A household reminder comprising a back member mounted to swing about a fixed axis, the back member having thereon a series of 20 names of household commodities, a channel member on the back member presenting spaced flanges having series of alined openings, a series of pins slideable in the openings of the flanges to extended positions beyond opposite sides of the channel member, and in one extended position 25 partially obscuring said names respectively, the pins being freely slideable in the flanges and ar-
ranged to be moved to another extended position by said swinging motion of the back member, and heads and bent ends on the pins limiting move-
30 ment of the pins when moved in the direction of the names and limiting movement of the pins when moved to the pre-determined position by the swinging motion of the back member the said pins being of a length presenting an extended portion beyond the channel member in each ex-
35 tended position of substantially greater length than the space between the said flanges.
